(57) CLAIM

The ornamental design for a scrubbing sponge with handle and holder, as shown and described.

DESCRIPTION

FIG. 1 is a front perspective view of a scrubbing sponge with handle and holder showing our new design;

FIG. 2 is a front exploded elevational view thereof; and, FIG. 3 is a left side elevational view of the scrubbing sponge and handle, the right side being the mirror image thereof.

1 Claim, 1 Drawing Sheet
